DON E. PRATT, OF SAN FRANCISCO, CALIFORNIA.

INTERNAL-COMBUSTION ENGINE.

1,080,123.

Specification of Letters Patent.

Patented Dec. 2, 1913.

Application filed July 10, 1912. Serial No. 708,625.

To all whom it may concern:

Be it known that I, DON E. PRATT, a citizen of the United States, residing in the city and county of San Francisco and State of California, have invented certain new and useful Improvements in Internal-Combustion Engines, of which the following is a specification.

The hereinafter described invention relates to a new and improved internal combustion engine of the two cycle type, and particularly to a form of engine wherein the cylinders are so arranged that one exhaust valve suffices for all.

The principal objects of the invention are to provide an engine of the above type wherein the admission of the explosive mixture into the cylinders is controlled by suitable valves operated by the piston rods in the respective cylinders, and to provide an engine wherein the power generated by the charges of explosive gases is transmitted to the drive shaft by a cam ring carried thereby, and said drive shaft also carrying and controlling the operation of the exhaust valve for the cylinders.

A further and important object is to provide an engine in which the tappet valves are entirely dispensed with, and one which is simple and durable in construction, compact in arrangement, and thoroughly efficient in all of its operations.

The invention consists in a casing, a drive shaft extending upwardly therethrough, a plurality of cylinders mounted on said casing and arranged annularly relative to said drive shaft, pistons in said cylinders, a valve controlled gas intake in each of said cylinders, means carried by the drive shaft and acted on by the reciprocation of the pistons for rotating said shaft, and an exhaust valve carried by said shaft and common to all of said cylinders and adapted to intermittently register with each of said cylinders.

With the above mentioned and other objects in view, the invention consists in the construction and novel combination of parts hereinafter fully described, illustrated in the accompanying drawings, and pointed out in the claims hereto appended; it being understood that various changes in the form, proportion, size and minor details of construction, within the scope of the claims, may be resorted to without departing from

the spirit or sacrificing any advantages of the invention.

To fully comprehend the invention reference should be had to the accompanying drawings in which is disclosed one form of a completely constructed device for successively carrying out my invention, wherein—

Figure 1 is a longitudinal central sectional view of a four cylinder engine of my improved type, disclosing the cylinders and supporting casing therefor, the drive shaft and the cam ring carried thereby, the pistons, the intake valves controllable thereby, and the exhaust valve common to all of the cylinders and operable and carried by the drive shaft. Fig. 2 is a transverse sectional view taken on line 2—2 Fig. 1 disclosing the arrangement of the cylinders and the positioning of the exhaust valve relative thereto. Fig. 3 is a transverse sectional view taken on line 3—3 Fig. 1 disclosing the intake valves, and the manner of mounting the cylinders on the casing. Fig. 4 is a perspective view of the drive shaft carrying the cam ring removed from the engine. Fig. 5 is a transverse sectional view taken on the line 5—5, Fig. 1.

Referring more particularly to the drawings, the reference numeral 1 designates a suitable hollow cylindrical casing open at one end, and constructed with straight side walls 2, at the upper edge of which is formed an annular overhanging lip 3, and at the juncture of the said lip and side walls is formed an annular seat 4 which is adapted to receive the peripheral edge 4' of a driven circular plate 5, which closes the open end of the casing and which is provided in its center with an opening 6 through which is adapted to extend a shaft 7.

Screw threaded at their lower ends to the upper edges of rings 8, which rest at their outer portions on the overhanging lip 3 and at their inner portions adjacent the shaft 7 on the center of the plate 5, and mounted on the casing by the retaining rings 9 through which extend the securing bolts 10, are the engine cylinders 11, arranged annularly relative to the shaft 7 and the upper open or exhaust ends of which are curved toward each other, as in Fig. 1, and the openings therein are adapted to be controlled by the conical shaped exhaust valve 12 carried by the upper end of the shaft 7, the lower end of which is squared and is

received in a squared opening in the upper end of the drive shaft 13, the lower end of said shaft projecting through a suitable opening in the lower end of the casing 1. 5 The shaft 13 is supported in the casing by suitable anti-friction bearings 13' retained in a runway 13², by a suitable adjustable bushing 13³, and a coiled expansion spring 7' encircles the shaft 7 between the adjustable nut 7² and the loose collar 7³ surrounding the shaft, said spring seating the exhaust valve in its seat formed at the upper open ends of the cylinders, the collar 7³ being antifrictionally mounted by ball bearings 7⁴ positioned between the same and the overhanging flanges 7⁵ at the inner side of the retaining rings 9.

Each of the cylinders 11 is provided with the usual cooling water jacket 14 and the 20 spark plug 15, and is formed adjacent its lower end with an integral annular flange 16 which is spaced from the lower side walls of the cylinder, providing a by-pass 17, which communicates with the upper portion 25 of the cylinder through the apertures 18 extending around the cylinder at the juncture of the cylinder proper and the flange 16.

Mounted to reciprocate in each cylinder is a piston 19, having the usual packing rings 20 and having depending downwardly from the underside thereof a piston rod 21 which operates through a suitable opening in the plate 5 and extends downwardly within the interior of the casing 1. The piston rod is 35 bifurcated adjacent its lower end, in which bifurcation is rotatably mounted on a shaft 22, an idler roller 23 which rests on the upper edge surface of a cam ring 24, formed integral with the drive shaft 13, and which 40 extends upwardly around the same in spaced relation thereto, said cam ring being formed with an overhanging lip 25 which is frictionally engaged on its underside by a pin 26 projecting from the extreme lower end of 45 the piston rod 21. Each piston rod 21 reciprocates in vertical slots 27 and 28 arranged opposite each other, the slots 27 being formed in the inner surface of the vertical walls 2 of the casing 1, and the slots 50 28 formed in the outer surface of an annular flange 29 integral with and depending downwardly from the underside of the plate 5, the flange being interposed between the upper portion of the drive shaft 13 and the 55 annular cam ring 24.

Surrounding each piston rod 21, and positioned between the lower edge of the flange 16 and an inwardly projecting seat 30 formed on the inner wall of the ring 8, is 60 a valve plate 31, provided on its under bevelled surface with an annular groove 32 in which is positioned an annular flat packing ring 33, which is adapted to rest on the seat 30 when the plate 31 is in its lowermost 65 position, the upper edge 34 of the plate be-

ing of such a diameter as to rest against the underside of the flange 16 when the plate is in its uppermost position.

Suitable packing rings 35 are carried by the plate 31 and the same frictionally engage the piston rod 21 so that the plate and its associated parts, hereinafter termed an inlet valve, will be operated upon the reciprocation of the piston and when said piston moves in an upward direction will abut against the lower end of the cylinder between the walls of the flange 16. The exhaust valve 12 is provided with a channel 36 the upper end of which communicates with the atmosphere through the center of the valve, as at 37, and the lower end of said channel opens to the side of the valve 12, as at 38, and is of the same size as the open ends of the respective cylinders. Suitable ports 39 are arranged in the overhanging lip 3 in communication with the engine cylinders and are adapted to be connected in any suitable manner with a carburetor, not shown, for the supplying of a gaseous mixture to the respective engine cylinders.

The operation of the engine is as follows: The respective parts being assembled as in the drawings, and as the drive shaft is manually rotated in starting the engine, the action of the cam ring 24 will reciprocate the pistons 19, the piston being on its firing stroke, as at A, will have on its upward movement to this position, lifted the inlet valve plate 31 which frictionally engages the piston rod, from its seat, and the suction in the base of the cylinder caused by the upward movement of the piston will draw a charge of explosive mixture into the base of the cylinder behind the piston. Upon the explosion of the charge in the head of the cylinder, which was drawn therein on a previous suction stroke of the piston, the piston rod will be at a position B relative to the surface of the cam 24, and the impact of the explosion will force the idler roller 23 thereof against the downwardly sloping surface C of the cam, rotating the shaft and cam ring in the direction of the arrow—Fig. 1.

The piston moving downwardly on its power stroke, the same will seat the intake valve plate 31 and close the aperture 18 of the by-pass 17, compress the gases within the base of the cylinder until the idler roller 23 carried by the piston rod reaches a point D on the cam ring 24 when the piston will be in a position, as at E in Fig. 1, and the channel 36 of the exhaust valve 12 will register with the opening in the upper end of the cylinder just fired, and the piston will be below the apertures 18 of the by-pass 17, at which time the gases compressed in the base of the cylinder will rush upwardly through the by-pass 17, out into the upper end of the cylinder through the apertures 130

18, driving the dead gases within the upper end of the cylinder outwardly through the channel 36 in the exhaust valve 12. The exhaust valve remains open but for a short period, only while the piston in the cylinder just fired is traveling between the points E' and F on the cam, after which time the upwardly inclined surface G of the cam will be presented to the idler roller and the piston 10 ton elevated to its firing stroke, and the above operations will again be performed as described. The engine cylinders are so positioned and the cam ring 24 is so formed, that the above cycles of piston movement 15 occur at timed intervals in the respective cylinders.

From the above construction it will be observed that an explosive engine has been designed which may be operated when in either a vertical or horizontal position.

Any suitable lubricating system may be employed which will efficiently lubricate the various parts of my invention, but the same has not been shown.

25 Having thus fully described my invention what is claimed as new and is desired to protect by Letters Patent is—

1. In an internal combustion engine, the combination with a stationary casing, a drive shaft rotatably mounted therein, cylinders mounted on said casing and arranged circumferentially of said drive shaft, a piston slidably mounted in each of said cylinders, each of said cylinders provided at 30 its lower end with an inlet port for the admission into said cylinders of an explosive charge and at its upper end with a normally closed exhaust port for the escape of the exploded gases from within said cylinders, 35 a valve carried by each of said pistons and operated by the movement thereof for controlling said inlet ports, a cam carried by said drive shaft and coöperating with said pistons for transmitting power therefrom to said drive shaft, 40 a valve carried by each of said pistons and operated by the movement thereof for controlling said inlet ports, a cam carried by said drive shaft and coöperating with said pistons for transmitting power therefrom to said drive shaft, a valve associated with each of said piston rods and operatable by the movement thereof for controlling the inlet port and admission into the cylinders of an explosive charge, means within each cylinder for firing the explosive charge contained therein, a rotary conical shaped exhaust valve carried by the end of said shaft 45 and positioned in a conical opening arranged centrally between the upper ends of said cylinders and operated by the rotation of said drive shaft for intermittently opening the exhaust ports of the cylinders to the atmosphere for permitting the escape of the exploded gases contained within the cylinders and means under tension 50 and associated with said shaft for maintaining said valve seated.

2. In an internal combustion engine, the combination with a casing, a stationary drive shaft rotatably mounted therein, cylinders mounted on said casing and arranged circumferentially of said drive shaft, a piston slidably mounted in each of said cylinders, 55 each of said cylinders provided at its lower end with an inlet port for the admission into said cylinders of an explosive charge and at its upper end a normally closed exhaust port for the escape of the exploded gases 60 from within said cylinders, a valve carried

by each of said pistons and controlled by the movement thereof for controlling said inlet ports, a cam carried by said drive shaft and coöperating with said pistons for transmitting power therefrom to said drive shaft, 70 means within each cylinder for firing the explosive charge contained therein, and a rotary exhaust valve carried by the end of said drive shaft, and arranged centrally of the upper ends of said cylinders, said valve provided with an angularly disposed port adapted upon the rotation of said valve to intermittently register with the exhaust ports of the cylinders for permitting the escape to the atmosphere of the exploded 80 gases from within the cylinders.

3. In an internal combustion engine, the combination with a stationary casing, a drive shaft rotatably mounted therein, cylinders mounted on said casing and arranged circumferentially of said drive shaft, a piston slidably mounted in each of said cylinders, a piston rod depending therefrom and extending within said casing, each of said cylinders provided at its lower end with an inlet port for the admission into said cylinders of an explosive charge and at its upper end with a normally closed exhaust port for the escape of the exploded gases from within said cylinders, a cam carried by said drive shaft and coöperating with said piston rods for transmitting power therefrom to said drive shaft, a valve associated with each of said piston rods and operatable by the movement thereof for controlling the inlet port and admission into the cylinders of an explosive charge, means within each cylinder for firing the explosive charge contained therein, a rotary conical shaped exhaust valve carried by the end of said shaft 90 and positioned in a conical opening arranged centrally between the upper ends of said cylinders and operated by the rotation of said drive shaft for intermittently opening the exhaust ports of the cylinders to the atmosphere for permitting the escape of the exploded gases contained within the cylinders and means under tension 95 and associated with said shaft for maintaining said valve seated.

4. In an internal combustion engine, the combination with a stationary casing, a drive shaft rotatably mounted therein, a driven shaft detachably secured to and operated by said drive shaft, cylinders mounted on said casing and arranged circumferentially of said driven shaft, a piston slidably mounted in each of said cylinders, a piston rod depending therefrom and extending within said casing, each of 100 said cylinders provided adjacent its lower end with an inlet port for the admission into said cylinders of an explosive charge and at its upper end a normally closed exhaust port for the escape of the exploded gases 105 from within said cylinders, a valve carried 110

from within said cylinders, a cam carried by said drive shaft and coöperating with said piston rods for transmitting power therefrom to said drive shaft, a compression chamber surrounding the lower end of each cylinder, a valve associated with each of said pistons and operatable by the movement thereof for controlling the admission into the cylinders and compression chambers of an explosive charge, means within each cylinder for firing the explosive charge contained therein, a rotary conical shaped exhaust valve carried by the end of said driven shaft, said valve provided with an angularly disposed exhaust port communicating at one end with the atmosphere and positioned in a conical opening arranged centrally of the upper ends of said cylinders and adapted upon the rotation of said valve to intermittently register with the exhaust ports of the cylinders for permitting the escape of the dead gases therefrom and spring pressed means interposed between the lower end of said driven shaft and said casing for maintaining said valve seated.

5. In an internal combustion engine, the combination with a stationarily mounted casing, a drive shaft rotatably mounted therein, a driven shaft operated by said drive shaft, a cylinder mounted on said casing, a piston slidably mounted in said cylinder, said cylinder provided at its lower end with a valve controlled inlet port for the admission thereto of an explosive charge and at its upper end with a normally closed exhaust port for the escape of the exploded gases therefrom, a cam carried by said drive shaft and coöperating with said piston for transmitting power therefrom to said drive shaft, means for firing the explosive charge within said cylinder, a conical valve seat associated with the upper end of said cylinder, a conical shaped rotary exhaust valve positioned in said valve seat and carried by the end of said driven shaft said valve being operated by the rotation of said drive shaft for intermittently opening the exhaust port of said cylinder for permitting the escape to the atmosphere of the exploded gases contained therein, and spring pressed means associated with the lower end of said driven shaft for retaining said valve in its seat.

6. In an internal combustion engine, the combination with a stationarily mounted casing, a drive shaft rotatably mounted therein, a driven shaft operated by said drive shaft, cylinders mounted on said casing and arranged circumferentially of said driven shaft, a piston slidably mounted in each of said cylinders, a piston rod depending therefrom and extending within said

casing and connected to said drive shaft, fuel chambers in said casing adjacent the lower end of each of said cylinders, a connection between each of said fuel chambers and a source of fuel supply, a communication between each of said fuel chambers and said cylinders, a valve associated with each of said piston rods and operatable by the movement thereof for controlling the communication between said fuel chambers and said cylinders, said cylinders provided at their upper end with a normally closed exhaust port for the escape of the exploded gases from within the cylinders, means for firing the explosive charge within the cylinders, and an exhaust valve common to all of said cylinders and operated by the rotation of said drive shaft for successively opening the exhaust ports of the cylinders to the atmosphere.

7. In an internal combustion engine, the combination with a stationarily mounted casing, a drive shaft rotatably mounted therein, a cylinder mounted on said casing, a piston slidably mounted in said cylinder, a piston rod depending therefrom and extending within said casing, a cam carried by said drive shaft and coöperating with said piston rod for transmitting motion therefrom to said drive shaft, said casing being provided with a fuel chamber, a communication between the fuel chamber and a source of fuel supply, a communication between the fuel chamber and the lower end of said cylinder, a valve associated with said piston and operatable by the movement thereof for permitting an explosive charge to be drawn into the cylinder through the last mentioned inlet communication on the upward stroke of the piston, and said valve adapted to close said last mentioned inlet communication on the downward stroke of the piston, said cylinder being further provided adjacent its lower end with a compression chamber communicating at its upper and lower ends with the interior of said cylinder, said piston on its downward movement compressing the gases into said chamber and controlling the upper communication between said compression chamber and the interior of said cylinder, means for firing the charge within the cylinder and a valve controlled exhaust port for the escape of the exploded gases therefrom.

In testimony whereof I have signed my name to this specification in the presence of two subscribing witnesses.

DON E. PRATT.
